US00D543177S

(12) **United States Design Patent** (10) **Patent No.:** **US D543,177 S**
(45) **Date of Patent:** **** May 22, 2007**

(54) **MOBILE COMMUNICATIONS DEVICE**

(75) Inventors: **Sang Beom Kim**, Durham, NC (US);
Charles C. Hunt, Wake Forest, NC
(US)

(73) Assignee: **Sony Ericsson Mobile
Communications AB**, Lund (SE)

(**) Term: **14 Years**

(21) Appl. No.: **29/244,680**

(22) Filed: **Dec. 13, 2005**

(51) **LOC (8) Cl.** **14-03**

(52) **U.S. Cl.** **D14/138**

(58) **Field of Classification Search** D14/137,
D14/138, 147, 218, 341-347; 455/90.3, 575.1,
455/575.3, 575.4; 379/433.01-433.13; 361/814;
348/14.02

(57) **CLAIM**

The ornamental design for a mobile communications device, as shown and described.

DESCRIPTION

FIG. 1 is a front perspective view of a mobile communications device showing our design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The solid line immediately adjacent the unshaded area that includes the broken line keypad, represent the boundary of the claimed design. The broken lines are directed to environment, and are for illustrative purposes only; The broken lines form no part of the claimed design.

1 Claim, 2 Drawing Sheets
